UNITED STATES PATENT OFFICE.

JOSEPH V. M. NOYE, OF LOWELL, MASSACHUSETTS.

AUTOMATIC-GUN HOLSTER.

1,173,376.

Specification of Letters Patent. Patented Feb. 29, 1916.

Application filed July 20, 1915. Serial No. 40,877.

To all whom it may concern:

Be it known that I, JOSEPH V. M. NOYE, a citizen of the United States, residing at Lowell, in the county of Middlesex and State 5 of Massachusetts, have invented certain new and useful Improvements in Automatic-Gun Holsters, of which the following is a specification.

This invention relates to holsters for pistols, revolvers and similar small arms, and more particularly to holsters for automatic guns of this class. Its object is to provide 10 a holster which will securely hold the gun in position so that it cannot shake out or 15 slip out while the wearer is running, scuffling, etc., but from which the wearer can instantly draw the gun with his hand by a natural movement.

My holster is especially adapted to be carried 20 in a pocket such as the hip pocket and is particularly useful for police officers and other civil officers. The holster for such persons is arranged to be readily attached or detached to the pocket and to rest securely 25 therein in such a manner that it will always be at the same place. The holster may be used, however, by military men and officers attached to a belt or other suitable hanger.

30 In the drawings, Figure 1 is a front elevation of my holster with a gun in position therein and also shows by dotted lines the first position of the wearer's hand in reaching for it, and by dotted lines, the position 35 of the pocket. Fig. 2 is an elevation as from the left of Fig. 1 with the hand omitted but with part of the garment and pocket shown in full lines but broken away to show the device for attaching the holster to the 40 pocket. Fig. 3 is a front elevation similar to Fig. 1 except that the garment and the hand are shown in full lines, the hand being shown in what might be called the second position. Fig. 4 is a view similar to 45 Fig. 3 with the hand in what may be called the third position in the act of drawing the gun from the holster. Fig. 5 is an elevation from the left of Fig. 4. Fig. 6 is a front elevation of a modified construction 50 having a short pocket for the gun muzzle and a small cap for the heel of the butt of the stock. It also shows the manner of attaching to a belt. Fig. 7 is an elevation from the left of Fig. 6.

55 In the preferred form of my holster shown in Figs. 1 to 5, A represents the

back member or rear wall which is made of relatively stiff material such as heavy leather, or leather reinforced by a metal plate or by a plate of other stiff material. 60 This rear wall is of substantially rectangular shape with rounded corners and is intended to fit loosely in the pocket P of a garment G, usually the hip pocket, in such a way that bottom edge 10 will rest on the 65 bottom of the pocket and the top edge 11 will project a short distance out of the pocket.

The front wall B is attached, usually by stitching, to the rear wall and is so shaped 70 or stitched or both that it conforms roughly to the barrel, muzzle, trigger guard and other parts of the gun so that these parts may be inserted in the holster pocket formed thereby with a comfortable fit. This front 75 wall is cut away at 20 to allow the handle or stock C of the gun to project substantially its entire length or a sufficient distance to permit it to be readily grasped by the hand of the wearer. At the same time 80 it is desirable that this cut away part 20 should afford some support for the front 30 of the handle or that the part 21 of the holster pocket should fit the muzzle 32 and adjoining portions of the barrel 33 with 85 sufficient snugness so that the weight of the stock C will not upset the gun or cause it to fall out of position. To the upper part 90 of rear wall A at a point diagonally opposite from the muzzle holding part 21 of the holster pocket, I attach to the top edge a flexible cap preferably made of soft leather. Preferably the rear wall is cut away with a downward, leftward slant at 22 and cap D is fastened along the diagonal line at 22 in 95 a substantially horizontal direction. This cap is formed with a curved wall 40 adapted to cover part of the back of the stock of the gun and to extend down to the heel 34 of the butt 35 and should be attached to the top of the rear wall in a substantially horizontal direction. The other portion 41 is of substantially ovoid shape and is attached, preferably by sewing, to the curved wall 40 of the cap so that they form a pocket at 100 their junction into which the heel 34 of the butt 35 of the stock C of the gun can enter.

I prefer to extend down the wall 40 of the flexible cap at 42 in a loose flap to cover the right side of the stock C to protect the 110 clothing of the wearer, and to make it easier to slip off the cap when about to draw, and I

prefer to extend down a flap 43 of 41 to cover the whole of the butt 35 for the same reasons. This cap D should fit over the butt loosely in order that it may be readily 5 swung to the front to slip over the heel of the butt and to be swung back away therefrom.

A glance at Fig. 6 will show that in a 10 holster of my construction, the gun is held at the muzzle and fore-part of the barrel by the holster pocket and at the heel of the butt by my flexible cap. In the construction shown in Figs. 1 to 5, there is more material used in the cap for the reasons indicated, and the cut away portion 20 of 15 front wall B also supports the gun at the front of the stock.

The operation is as follows:—When about 20 to draw the gun, the wearer carries a hand H down over the pocket P preferably below 25 the stock with the fingers and thumb extended as shown. A natural or easily acquired movement is to feel with the thumb 55 for the barrel and with the little finger 51 for the butt as shown in Fig. 1. The hand is then swept upward, as shown in Fig. 3, so that the little finger 51 will engage either a member 40 or 41 or the extensions thereof 42 or 43. The little finger 30 naturally slips upward along the butt or the side of the stock ahead of the other fingers and pushes the cap D back over the heel and stock and out of the way as shown in Figs. 4 and 5. While this is being done, 35 the other fingers 50, 52 and 53 are curling under the front 30 of the stock while the thumb 55 slips around the back end 36 of the barrel into its proper position at the left of the stock, as shown in Figs. 4 and 5 in 40 which parts of the hand are broken away the better to show the action. In replacing the gun in the holster, the cap is disregarded until the gun is in position, after which the cap may be readily slipped over 45 in place by a natural movement of the little finger.

To securely position my holster in a 50 pocket in order that the cut away portion 20 of the front wall may be proximate and preferably slightly above the top 27 thereof, I prefer to have the rear wall of such length that its bottom edge will reach and rest on the bottom of the pocket, I then prefer to attach a snap 14 with an opening on the inside of the pocket, in position to naturally receive a snap head 15 preferably attached to the front wall B. The whole holster may thus be put in position or detached with facility and rapidity. Any means for so 55 positioning the holster in a pocket as to allow the stock to project may be used. The butt flap 43 and side flap 42 should also clear the top of the pocket.

In the construction shown in Figs. 6 and 7, 65 the rear wall K is shown as being, instead

of rectangular, roughly of the form of the gun itself, while the front wall L, located at the lower right hand part thereof, forms a relatively short holster pocket which will receive with fair snugness the muzzle and 70 front of the barrel of the gun. At the upper left hand portion of rear wall K is a short cap 60 which extends over the heel of the butt of the stock with its lower front edge cut on a line in a plane running diagonally from a point 61 on the upper edge 63 to a point 62 on the left edge 64, the point 61 being preferably a considerable distance farther away from the upper left-hand corner of the holster than is the point 80 62. This construction is quite satisfactory for certain purposes although the gun is not as well protected from dust and from the weather. The holster shown in Figs. 6 or 7 75 may be provided with loops 73 through 85 which a belt 74 may be passed. With this latter form of holster, it is highly necessary that the back wall should be substantially rigid.

I claim:

1. An automatic gun holster having a 90 relatively stiff rear wall, a flexible cap attached thereto in a substantially horizontal direction and adapted to slip from the rear over the heel of the butt of the stock of the gun.

2. An automatic gun holster having a relatively stiff rear wall, a front wall so attached thereto as to form a holster pocket for the muzzle of the gun, and a relatively 100 flexible cap attached to the rear wall in a position diagonally opposite from the bottom of the holster pocket and adapted to slip from the rear over the heel of the butt of the stock of the gun.

3. An automatic gun holster having a relatively stiff rear wall, a front wall forming a holster pocket for the gun attached to the front thereof and cut away to allow the stock of the gun to project, and a relatively flexible cap attached in a substantially 110 horizontal direction to the top of the rear wall and adapted to slip from the rear over the heel of the butt of the stock of the gun.

4. An automatic gun holster having a relatively stiff rear wall, a front wall so attached as to form at the lower right hand part thereof a holster pocket for the muzzle of the gun, and a relatively flexible cap so attached to the upper left hand corner of the rear wall that it can be slipped over the heel of the butt of the stock of the gun.

5. An automatic gun holster having a relatively stiff rear wall, a front wall so attached as to form at the lower right hand part thereof a holster pocket for the muzzle of the gun, and a relatively flexible cap so attached to the upper left hand corner of the rear wall that it can be slipped over the heel of the butt of the stock of the gun, to 125 130

gether with means on the front wall of the holster for readily attaching the holster to a pocket.

6. An automatic gun holster having a 5 relatively stiff rear wall and a flexible cap so attached thereto as to swing to the front and slip over the heel of the butt of the stock of the gun and to swing back away therefrom.

10 7. An automatic gun holster having a flexible cap adapted to slip from the rear over the butt of the gun.

8. An automatic gun holster having a 15 relatively stiff rear wall, a front wall forming a holster pocket for the gun attached to the front of the rear wall and cut away to allow the stock of the gun to project, and a relatively flexible cap attached in a substantially horizontal direction to the top of the

the rear wall having a butt flap and a side 20 flap and adapted to slip over the heel of the butt of the stock of the gun.

9. An automatic gun holster having a 25 relatively stiff rear wall, a front wall forming a holster pocket for the gun attached to the front thereof and cut away to allow the stock of the gun to project, and a relatively flexible cap attached in a substantially horizontal direction to the top of the rear 30 wall having a butt flap and a side flap and adapted to slip over the heel of the butt of the stock of the gun, together with means for so positioning the holster in a pocket as to allow the stock of the gun to project.

In testimony whereof I hereto affix my 35 signature.

JOSEPH V. M. NOYE.
